CAR DOOR CONSTRUCTION

Wilfred A. Beauchamp, Chicago, Ill., assignor, by
mesne assignments, to The Youngstown Steel
Door Company, Cleveland, Ohio, a corporation
of Ohio

Application April 26, 1932, Serial No. 607,630

23 Claims. (Cl. 20—21)

This invention relates to car door construction, applicable to railway house cars, including refrigerator cars, and concerns itself more particularly with flush door for all types of railway house cars.

It is an object of this invention to provide outside doors for railway house cars, which doors shall be flush with the outer plane of the doorway or with the outer plane of the car side and shall require a straight line sliding movement longitudinally of the car only in their travel toward open and closed positions.

A further object is to provide sliding doors for a stream line freight car, said doors being arcuate to carry on the stream line effect of the car and exposing a minimum of its fixtures beyond the sides of the car.

A further object is to provide a flush straight line sliding door for a railway house car which is provided with side walls of substantially uniform depth.

A further object is to provide a flush straight sliding door for freight cars adapted to be supported for movement upon the sill of the car.

A further object is to provide a railway house car having a straight sliding door and a laterally movable side wall section, the door and the section in their closed positions lying flush with the outer plane of the side wall.

A further object is to provide a railway house car having a side wall of substantially uniform depth, a section of said wall being capable of lateral movement relative to the car, and a door adapted to be positioned in alignment with said section in the closed positions thereof and to be positioned in the space vacated by the section in its lateral movement.

A further object is to provide a railway house car having a straight sliding door and a side wall section capable of lateral movement, the section abutting the door in its closed position to seal and maintain the door in said position.

A further object is to provide a railway house car having a straight sliding door and a side wall section capable of lateral movement, the vertical edges of the door converging outwardly and the adjacent edge of said section and the front door jamb converging outwardly whereby the abutment of the section against the door forces the door into tight engagement with the car.

A further object is to provide a railway house car having a side wall composed of a fixed section and a laterally movable section adjacent the door opening provided in said wall.

A further object is to provide a railway house car having a side wall formed of stationary and laterally movable sections adjacent a door opening provided in the wall, the movable section in its closed position being locked in abutting engagement with the stationary section to reinforce the latter.

A further object is to provide a sliding door for refrigerator cars having novel automatic and sealing structure provided at the top and bottom thereof.

Other objects will become apparent as the description of this invention proceeds.

In the drawings forming part of this specification

Figure 1 is a fragmentary elevation illustrating the invention applied to a stream line house car.

Figure 2 is a horizontal section taken on line 2—2 of Figure 1.

Figure 3 is a horizontal section showing the door in open position and the corresponding position of the movable section of the wall.

Figure 4 is a horizontal section taken on line 4—4 of Figure 1.

Figure 5 is a vertical section taken on line 5—5 of Figure 1.

Figure 6 is a vertical section taken on line 6—6 of Figure 1.

Figure 7 is a fragmentary elevation showing the invention applied to a refrigerator car.

Figure 8 is a horizontal section taken on line 8—8 of Figure 7.

Figure 9 is a horizontal section illustrating the door in open position and the corresponding position of the movable section of the wall.

Figure 10 is a vertical section taken on line 10—10 of Figure 7.

Figure 11 is a vertical section taken on line 11—11 of Figure 7.

Referring to the embodiment of the invention illustrated in Figures 1 to 6, inclusive, the numeral 10 designates generally a railway house car. As illustrated in this embodiment of the invention the house car 10 is provided with an outer arcuate surface 11 to provide a stream line effect of the car the door 12 and the movable section 13 of the side wall are similarly arcuated. Moreover, this effect is extended to the fixtures applied to the car. The hangers 14 for the door are positioned within the inner and outer planes thereof so as not to project beyond the side of the car while the guide brackets 15, actuating mechanism 16 and hinges 17 are so formed as to

5

10

15

20

25

30

35

40

45

50

55

present a minimum of resistance to the travel of the car. Fixed handles 18 and 19 are secured to the door within offset portions 20 provided therein to decrease the projection of said handles from the door.

The house car 10 is provided with an opening 21 adapted to be closed by the sliding door 12. Adjacent the opening 21 the side wall 22 of the car is formed of an inner stationary section 23 and an outer movable section 24 which, as clearly illustrated in Figure 2 of the drawings, is adapted to have overlapping engagement with one margin of the door 12 and to lie substantially flush with said door. Additionally, the door 12 and the movable section 24 are substantially flush with the outer plane of the side wall 22 of the car. It is to be observed, moreover, that the combined depths of the stationary wall section 23 and the movable wall section 24 is substantially the same as the depth of the remainder of the side wall 22.

The side wall 22 is preferably formed of a plurality of pan-shaped panels 25 provided with inwardly extending flanges 26 and 27 positioned in abutting relationship and secured together preferably by means of welding. The panel adjacent the forward edge of the door 12 is provided with an inwardly and forwardly inclined portion 28 adapted to engage a correspondingly inclined portion 29 formed at the forward edge of the door. The panel 25 at the rear edge of the movable section 24 is provided with an inwardly and rearwardly inclined portion 30, adapted to overlie a correspondingly inclined portion at the rear margin 31 of the movable section. Similarly inclined portions 32 and 33 are provided on the rear margin and on the forward margin of the door and movable section, respectively.

The car 10 embodies in its construction, a plurality of side sills. A side sill 34 is clearly illustrated in Figures 5 and 6 of the drawings and projects outwardly beyond the door opening 21 and the stationary section 23 of the car, the outer plane of said side sill lying substantially flush with the outer plane of the side wall of the car. Referring again to Figure 5 of the drawings it will be observed that the projecting portion at the side sill serves as a track upon which the door 12 is adapted to slide in its travel toward open and closed positions. In the normal or closed position of the door 12 and the movable section 24, said section as well as the door overlie the projecting portion of the sill. Moreover, in the normal position of the door and the movable section the engagement therebetween prevents travel of the door toward open position. To permit such travel of the door the movable section must be displaced relative to the projecting portion of the sill which it overlies.

To this end the movable section at its rear margin is supported upon the side wall of the car by means of the plurality of hinges 17. These hinges as clearly shown in Figures 2 and 3 of the drawings, are preferably of the multiple pintle type, each comprising a strap portion 35 secured to the movable section, a strap portion 36 secured to the panel 25 and links 37 secured at the respective ends thereof to the strap portions 35 and 36 by means of the pintles 38 and 39. It will be observed that the hinges 17 permit both lateral and longitudinal movement of the rear margin of the section.

The actuating means 16 is utilized adjacent the forward margin of the movable section for

actuating said section to effect lateral and longitudinal movement thereof. This means, in the present embodiment of the invention, employs a vertical bar 46 rotatably secured to the section by means of a plurality of brackets 41. The ends of said bar are provided with cranks 42 and 43, the ends 44 and 45 of which are rotatably secured to the car by means of brackets 46 and 47. A lever 48 is secured to the bar in order to effect rotation thereof, said lever being adapted to be secured to said section by any desired fastening means, such as shown generally at 49.

It will be apparent that upon release of the lever 48 from the fastening means 49 and swinging of said lever to the left as viewed in Figure 1 of the drawings rotation will be imparted to the bar which will impart a lateral movement and a longitudinal movement to the forward edge of the movable section. These movements will also occur at the rear edge of said section because of the construction of the hinges 17. The movable section upon operation of the actuating mechanism 16 will finally assume the position shown in Figure 3 of the drawings. The outward position of the section 24 as shown in said figure will expose the projecting portion of the side sill 34, heretofore covered by said section. Either of the handles 18 and 19 may then be grasped and the door 12 moved upon the side sill to its open position. In said position of the door the handles 18 and 19 will lie forwardly of the movable section so that the door may readily be returned to its closed position. Movement of the door to its closed position and operation of the actuating mechanism in the reverse direction will restore the door and the movable section to their normal or closed positions, as clearly shown in Figure 2 of the drawings. The forward edge of the door will be maintained in sealing engagement with the adjacent panel of the car and the rear edge of the movable section 24 will be maintained against outward movement by the overlying portion 30 of the panel 25. As the movable section is actuated to its normal or closed position the portion 33 of the forward edge thereof will engage the portion 32 at the rear edge of the door and exert a longitudinal thrust to said door to insure positioning of the door in its fully closed position. This overlapping will additionally produce an inward pressure upon the door so as to cause it to seat itself against the adjacent fixed portions of the car. When the lever 48 is fastened in position the movable section serves to fasten the door in its closed position and, also, to provide a tight sealing engagement between the section and the adjacent portion of the door. To complete sealing engagement around the four edges of the door the top and bottom thereof are provided, respectively, with plates 50 and 51 adapted to engage the adjacent portions of the car. A substantially Z-shaped member 52 secured preferably by welding to the car overlaps the plate portion 50 secured to the upper horizontal margin of the door, enhancing the weatherproofing qualities at said margin of the door and serving additionally as a guide and retainer therefor in its opening and closing movement. At its lower margin the door is guided and retained against disengagement from the track by means of the brackets 15. Weather excluding plates 53 and 54, coacting with the car are provided at the top and bottom, respectively, of the movable section. It is to be noted that the guide brackets 15 are curved and that the panel 25 and the rear margin of the movable section 24 are recessed as indi-

cated at 55 and 56, respectively, to reduce the projection of the hinges 17 for the purpose of decreasing the air resistance upon the car in transit.

5 The door 12 is composed of a metallic panel 57 and is provided preferably with a wooden frame 58. The movable section 24 comprises a metallic panel 59 and is provided with vertical framing members 60 and 61, preferably constructed of wood. The framing member 60 of the movable section, because of the engagement between said section and the door 12 serves as a jamb for the door.

10 The invention as applied to a refrigerator car is illustrated in Figures 7 to 11, inclusive, of the drawings. The refrigerator car 62 is illustrated as formed of wood and is provided with the customary insulating material 63. As in the previous embodiment of the invention the car 62 is provided with a door opening 64 adapted to be closed by means of a straight sliding door 65, also formed of wood, and provided with the insulating material 63. Adjacent the door opening the side wall 66 of the car is formed of a stationary section 67 and a laterally movable section 68. The engagement between the door and the laterally movable section and the engagement between said door and its adjacent fixed jamb and between the movable section and the adjacent wall remains the same as that in the heretofore described embodiment of the invention. The movable section 68 is provided with a vertical framing portion 69 which serves as a jamb for the adjacent margin of the door. Spring control weather stripping material 70 is provided in the vertical margins of the door. The movable section 68 is hingedly secured to the car by means of the hinges 71 differing slightly in detail from the hinges 17. These hinges are secured to the rear margin of the movable section, the front margin thereof carrying the actuating mechanism 16 heretofore described.

15 A track 72, secured to the side sill 73, is adapted to support the door 65 for sliding movement. As clearly shown in Figure 10 of the drawings, a portion of the door lies within the outer plane of the car. A threshold plate 74 is secured adjacent the side sill and a plate 75 is secured to the car above the inwardly projecting portion of the door. These plates are provided with vertically aligned indentations 76 and 77, respectively. The lower margin of the inwardly projecting portion of the door is recessed as indicated at 78 and is adapted to receive brackets 79 provided with vertical rollers 80. A helical spring 81 abuts one end of the recess 78 and receives a spindle 82 formed on the bracket 79 and abuts a shoulder 83 formed at the lower end of said spindle. The bracket 79 is seated within a recess formed in a wooden filler 84, positioned in the recess 78 formed in the door and extending for the width of the door, and is secured thereto by means of bolts. A weather strip 85 is secured at one end to the inner face of the inwardly projecting portion of the door and at its other end to the outer face of the filler 84. The weather strip 85 is continuous for the entire width of the door. The upper margin of the inwardly projecting portion of the door is similarly formed, the parts thereof being reversely arranged from the corresponding parts described for the lower margin of the inwardly projecting portion.

20 It will be apparent from the foregoing description of the construction and parts of the upper and lower portions of the inwardly projecting part

of the door that when the door is in its fully closed position the rollers 80 will be seated within the depressions 76 and 77. The seating of the rollers in the portions 76 and 77 will be aided by the springs 81. In this position of the rollers the filler blocks 84 will engage the weather strips 85 at the top and bottom of the door and, under the influence of the springs, force the sealing strips into tight engagement with the plates 74 and 75, forming a tight seal at the upper and lower portions of the inwardly projecting part of the door. When the door is moved toward open position the rollers 80 will ride out of the depressed portions 76 and 77 and, together with the roller brackets and wooden fillers, be forced against the tension of the springs 81 further into the recesses 78. In consequence of this movement the weather strips 85 will be retracted and will be maintained by the rollers out of engagement with the plates 74 and 75 so as to prevent wear on said weather strips.

25 It is manifest from the foregoing that sealing constructions are provided around the four edges of the door and, also, that by virtue of the weatherproofing strips secured to the upper, lower and rear edges of the movable section such section also maintains sealing arrangements around its perimeter.

30 From the foregoing description of the embodiments of the instant invention there is presented a car construction in which the door, movable section and the adjacent side wall are flush with the car, or a construction in which the adjacent portions of the door, side wall and movable section and the adjacent portions between the movable section and the side wall are flush.

35 Numerous changes and modifications in the details of the embodiments of the invention disclosed will be apparent to those skilled in the art. It is intended, therefore, that all such changes and modifications shall be comprehended within this invention, which is to be limited only by the scope of the claims appended hereto.

I claim:

1. In a railway house car, in combination, a side wall having a door opening, a fixed door jamb positioned at one side of said opening, a sliding door for closing said opening adapted, in its closed position, to engage said fixed jamb and to lie upon the outside of said wall at the opposite side of said door opening, and a movable jamb mounted upon the outside of said wall and adapted to engage said door in its closed position.

2. In a railway house car, in combination, a side wall having a door opening, a fixed door jamb positioned at one side of said opening, a sliding door for closing said opening adapted, in its closed position, to engage said fixed jamb and to lie upon the outside of said wall at the opposite side of said door opening, and a laterally movable jamb mounted upon the outside of said wall and adapted to engage said door in its closed position.

3. In a railway house car, in combination, a side wall having a door opening, said wall adjacent said opening being formed of a stationary wall section and a movable wall section, a fixed jamb positioned at one side of said opening, a sliding door adapted, in its closed position, to engage said jamb and to lie outwardly of said stationary wall section, a jamb secured to said movable wall section for movement therewith, said jamb adapted to engage said door in its closed position.

4. In a freight car, in combination, a wall provided with a door opening, said wall adjacent said opening including a stationary section and a movable section, a sliding door adapted to close said opening, said movable section lying in the path of opening movement of said door and being movable laterally from said stationary section to permit opening movement of said door.
5. In a freight car, in combination, a wall provided with a door opening, said wall adjacent said opening having a stationary section and a movable section, a sliding door adapted to close said opening and to be overlapped by said movable section, and means for locking said movable section, whereby to maintain said door in closed position.
6. In a railway freight car, in combination, a wall provided with a door opening, a door for closing said opening, said wall contiguous to said opening comprising a stationary section and a laterally overlapping movable section, and means for securing said sections together in the closed position of said door whereby said movable section reinforces said stationary sections.
7. In a railway freight car, in combination, a wall having a door opening, a sliding door for closing said opening, said wall adjacent said opening comprising a stationary section and a movable section, said door lying outwardly of said stationary section and flush with said movable section, said movable section being hinged to said wall for lateral movement relative thereto to permit opening movement of said door.
8. In a railway freight car, in combination, a wall having a door opening, a sliding door for closing said opening, said wall adjacent said opening comprising a stationary section and a movable section, said door lying outwardly of said stationary section and flush with said movable section, one vertical edge of said movable section being hinged to said wall and the opposite edge of said section being provided with means to effect lateral movement thereof.
9. In a railway freight car, in combination, a wall having a door opening, a sliding door for closing said opening, said wall adjacent said opening comprising a stationary section and a movable section, said door lying outwardly of said stationary section and flush with said movable section, one vertical edge of said movable section being hinged to said wall and the opposite edge of said section being provided with means to effect lateral movement thereof, said means comprising a vertical bar rotatably secured to said movable section and having cranks at the ends thereof, said cranks lying, respectively, above and below said section and having ends journaled in bearings fixed to said car and a lever for operating said bar.
10. In a railway car, in combination, a sliding door lying flush with the adjacent wall of said car, the front edge of said door being overlapped by said wall, a movable wall section having a front edge overlapping the rear edge of said door and lying flush therewith, the rear edge of said movable section being overlapped by the wall of said car adjacent thereto, said movable section lying flush with said wall.
11. In a railway car, in combination, a slidably door, a laterally movable section, said door being flush with said section in the closed position of said door, said section being movable bodily outwardly from said car, whereby said door may be moved to open position to occupy the space vacated by said section.
12. In a railway car, in combination, a side wall having a door opening, a slideable door for closing said opening, said wall adjacent said section comprising a stationary section and a movable section, said latter section lying in the path of opening movement of said door and movable laterally from said stationary section to provide a recess with the latter section, adapted to receive said door in its opening movement.
13. In a railway house car, in combination, a slideable door, a movable section, a side sill, said door being supported for sliding movement upon said sill, said section in its normal position having overlapping relationship with said sill and means for moving said section from its overlapping position with said sill, whereby said door may travel to open position supported upon the sill.
14. In a railway house car, in combination, a side wall provided with a door opening, a door for closing said opening, said wall adjacent said opening comprising a stationary section and a movable section, a side sill projecting outwardly beyond said door opening and said stationary section, said door being supported for sliding movement upon the projecting portion of said sill, said movable section lying in the path of opening movement of said door, and means for moving said section whereby said door may travel to open position.
15. In a railway house car, a sliding door, a door frame, a substantially horizontally positioned plate having spaced indentations therein provided in said frame and means provided on said door adapted for engagement with said plate to effect a weathertight joint therewith, said means comprising spaced rollers movable vertically relative to said door and weatherproofing material, said rollers adapted to be seated in said indentations to project said material into contact with said plate in the closed position of the door and to ride out of said indentations and upon the plate in the opening movement of said door to retract said material from said plate.
16. In a freight car, in combination, a wall provided with a door opening, said wall adjacent said opening including a stationary section and a movable section, a sliding door adapted to close said opening, said movable section lying in the path of opening movement of said door and being movable relative to said stationary section to permit opening movement of said door.
17. In a freight car, in combination, a wall provided with a door opening, said wall adjacent said opening comprising a movable section, a sliding door adapted to close said opening, said movable section lying in the path of opening movement of said door and being movable relative to said car to permit opening movement of said door.
18. In a freight car, in combination, a wall provided with a door opening, said wall adjacent said opening comprising a movable section, a sliding door adapted to close said opening, said movable section lying in the path of opening movement of said door and being movable laterally relative to said car to permit opening movement of said door.
19. In a railway freight car, in combination, a wall having a door opening, a sliding door for closing said opening, said wall adjacent said opening comprising an inner and an outer section, said door lying outwardly of said inner section and flush with said outer section, said outer section being hinged to said wall for lateral

movement relative thereto to permit opening movement of said door.

20. In a railway house car, in combination, a 5
slidable door, a section mounted upon and movable relative to said car, a track secured to said car, said door being supported for sliding movement upon said track, said section in its normal position having overlapping relationship with said track so as to lie in the path of travel of said door and means for moving said section from its overlapping position with said track whereby said door may travel to open position supported upon said track.

21. In a railway house car having members defining a door opening, in combination, a sliding door for closing said opening, spaced indentures provided in a horizontally extending member, a sealing strip carried by said door for engagement with said member in the closed position of the door, said strip being capable of vertical movement relative to said door and means seated in said indentures in the closed position of the door for elevating said strip above said member in the sliding movement of said door to open position.

22. In a railway freight car, in combination, a wall provided with a door opening, said wall contiguous to said opening comprising a stationary section and lateral overlapping movable section and means for securing said sections together whereby said movable section reinforces said stationary section, the combined depths of said sections being not greater than the depth of the remainder of said wall.

23. In a freight car, in combination, a 10
wall provided with a door opening, a movable section mounted adjacent said opening upon said car, a sliding door adapted to close said opening, said movable section lying in the path of opening movement of said door and being 15
movable relative to said car to permit opening movement of the door, said movable section engaging the rear margin of said door in the closed position thereof when said section is brought to home position, whereby to force said door tightly 20
closed and to cooperate with the rear margin thereof to provide a weatherproof construction.

WILFRED A. BEAUCHAMP. 25
